UNITED STATES PATENT OFFICE.

FREDERICK REHORN, OF NEW YORK, N. Y.

IMPROVED SAD-IRON HANDLE.

Specification forming part of Letters Patent No. 58,291, dated September 25, 1866.

To all whom it may concern:

Be it known that I, FREDERICK REHORN, of the city, and county, and State of New York, have invented a new and Improved Sad-Iron Handle; and I do hereby declare that the following is a full, clear, and exact description thereof, which will enable others skilled in the art to make and use the same, reference being had to the accompanying drawings, forming part of this specification, in which—

Figure 1 represents a side elevation of this invention. Fig. 2 is an end view of the same. Fig. 3 is a transverse section of the same, the line x x , Fig. 1, indicating the plane of section.

Similar letters of reference indicate like parts.

This invention relates to a movable handle for sad-irons, said handle being attached to the iron by a dovetail socket, and held in position by a lever-catch, which is pivoted to one of the standards of the handle, and which, when the handle is in position, catches over a cam and locks the handle firmly to the body of the iron.

The main part of said handle is cast of one piece, the standards being united by a cross-bar, to which the wooden handle is secured by simple pins, whereby the construction of the whole is greatly simplified, and its cost is reduced to proper limits.

A represents the body of a sad-iron, which is provided with a dovetailed socket, a , to receive the bottom end of the handle B.

This handle is composed of two standards, b , a bottom cross-bar, c , and a top cross-bar, d , and all these parts are cast solid out of one piece, so that the labor of fitting the handle is considerably reduced.

The top cross-bar d forms the bearing for the wooden handle C, which is turned and

provided with a slot, e , just large enough to catch over said cross-bar, as shown in Fig. 3, nothing being required but to drill two small holes in said cross-bar to receive the pins f , which fasten the wooden handle to said cross-bar.

After the handle B is introduced into the socket a the lever-catch D is turned down and made to catch in front of a cam, g , which projects from the body of the iron, and by these means the handle is firmly locked in its place and prevented from becoming detached spontaneously.

The catch-lever is pivoted to one of the standards b of the handle, and it is in such a position that it can be conveniently reached by the hand which grasps the handle.

The cam g forms an inclined plane, and as the end of the lever-catch moves up this incline the handle is drawn tight into its socket, and it can be readily united to sad-iron, so that the same will not shake, and both will appear as a solid piece.

A guard, F, prevents the radiating heat of the iron from coming in contact with the hand which grasps the handle.

What I claim as new, and desire to secure by Letters Patent, is—

1. The handle B, consisting of the top cross-bar d , standard b , and bottom cross-bar c , cast in one piece, and applied in the manner and for the purpose specified.

2. The grooved wooden handle C, in combination with the top cross-bar of the metal handle B, and with pins or other suitable fastenings, substantially as and for the purpose set forth.

FREDERICK REHORN.
